UNITED STATES PATENT OFFICE.

ELLA N. GAILLARD, OF EASTON, MARYLAND.

CLASP FOR HOSE-SUPPORTERS.

SPECIFICATION forming part of Letters Patent No. 678,654, dated July 16, 1901.

Application filed October 13, 1900. Serial No. 32,997. (No model.)

To all whom it may concern:

Be it known that I, ELLA N. GAILLARD, a citizen of the United States, residing at Easton, in the county of Talbot and State of Maryland, have invented a new and useful Clasp for Hose-Supporters, of which the following is a specification.

My present invention relates to a novel clasp for hose-supporters of that class in which the hose or fabric is held between a button or headed projection carried by one clasp member and the surface of a coöperating clasp member having an opening for the reception of the button and that portion of the hose retained by the clasp.

The objects of the invention are to improve the construction of the clasp by eliminating the loose connection between the clasp members, which is ordinarily necessary, and to eliminate the necessity for sliding the eye member relative to the button member for the purpose of effecting the attachment of the clasp to the garment or its detachment therefrom.

To the accomplishment of these objects and others subordinate thereto the invention consists in providing a button-supporting plate or member provided with a yielding button and an eye plate or member hinged to the first-named member and formed with an eye coöperating with the button and of varying diameter, the minimum diameter of said eye being slightly less or approximately the same as the maximum diameter of the button, to the end that said button covered by the fabric to be retained will be forcibly contracted as it passes the point of greatest constriction of the eye, the secure retention of the garment being assured by the necessity for a light contraction of the button in order to effect its withdrawal from the eye and the consequent release of the fabric.

The invention further consists in the construction and arrangement of parts to be hereinafter more fully described, illustrated in the accompanying drawings, and succinctly defined in the appended claims.

In said drawings, Figure 1 is a perspective view of my clasp, showing the eye and button members swung apart. Fig. 2 is a front elevation showing the members in engagement. Fig. 3 is an edge view. Fig. 4 is a

sectional view with the periphery of the button located within the point of greatest constriction of the eye. Fig. 5 is a sectional view on the line 5 5 of Fig. 2. Fig. 6 is a sectional view of a modification of the means for retaining the button upon its shank.

Referring to the numerals of reference employed to designate corresponding parts throughout the views, 1 and 2 indicate a pair of plates hinged together at a point adjacent to one end, as indicated at 3, and which in view of other characteristics to be described I will designate, respectively, as a "button" member and an "eye" member. At a point removed from the hinge and preferably adjacent to its opposite end the member 1 is provided with a shank 4, surmounted by a yielding button 5, secured upon the shank in any suitable manner and disposed for coöperation with an eye 6, formed in the eye member 2 at a point which will insure the presentation of the button to the eye when the members are swung together. The usual construction of clasps of this general character has comprehended the provision of an eye or loop of elongated form and having one end sufficiently large for the repassage of the button and the other end somewhat constricted for the reception of the shank as the eye member or loop is drawn longitudinally. Such construction necessitates a loose connection between the members of the clasp—as, for instance, the connection of said members to the ends of separate elastic strips. My invention contemplates the elimination of this loose connection and, as heretofore stated, the necessity for sliding the members relatively for the purpose of effecting the attachment or detachment of the clasp to or from the hose or other garment. These ends are attained by effecting the direct hinged connection of the plates and by the peculiar form of the eye, which merely requires the passage of the button therethrough in an axial direction in order to effect the attachment or release of the fabric. The eye 6 is formed by perforating the member 2 and by spinning up the metal surrounding the opening to form an annular flange 7, extending from the face of the eye member opposite the button member. The formation of this flange serves to increase the extent of the annular eye-defin-

ing wall, the interior face of which is of somewhat irregular form transversely in order to vary the diameter of the eye 6. This irregular form of the interior face of the wall

5 7 is productive, first, of a rounded corner 8, which prevents the cutting of the fabric as the latter is forced through the eye by the button, and, next, the annular constriction of the eye, as indicated at 9, this constriction 10 being disposed intermediate of the rounded corner 8 and a decided flare or enlargement of the eye, as indicated at 10.

By reference to the drawings it will be seen that the diameter of the yielding button 5 is 15 slightly greater than the diameter of the constricted portion 9 of the eye; but inasmuch as the button is designed to be covered by the fabric its diameter may be approximately the same as or even slightly less than that of 20 the constriction, inasmuch as the effective diameter of the button will be somewhat increased by the fabric, and will therefore compel sufficient contraction of the button as it passes through the eye to prevent its accidental withdrawal therefrom and the consequent release of the garment.

When attaching my clasp to a hose, the fabric is placed over the button 5 with the members 1 and 2 in the position shown in

30 Fig. 1. The members are then swung together, and the button is presented before the eye. Slight pressure upon the members will now cause the fabric-covered button to be forced through the eye, the rounded corner 8, constituting a slight flare of the inner end of the eye, serving to prevent the cutting of the fabric as the yielding button is forced past the constriction of the eye and into the flared outer end of the latter, at which latter 40 point the button may again expand to its normal dimensions and press the fabric firmly against the adjacent surface of the eye or, perchance, against the outer end of the flange 7. The fabric will thus be securely held 45 against casual or accidental release; but the detachment of the clasp therefrom may be quickly effected by inserting the thumb or finger under the thumb-piece 11, formed at the free end of the member 2, to facilitate the 50 separation of the members and the withdrawal of the button from the eye.

The separation of the button and eye members is limited, preferably, by reason of the peculiar form of the hinge 3. One of the 55 members—as, for instance, the member 1—is provided with a pair of transverse slots 12, through which pass a pair of curved hingelugs 13, extending from the end of the member 2 and headed at the opposite side of the 60 member 1, as indicated at 14, these heads co-operating with a shoulder 15, formed by the end of the member 2, to limit the relative swinging of the members. While the screw connection between the button and its shank, 65 as indicated in the first five figures of the drawings, is probably a preferable form of such connection, an example of a possible va-

riation is illustrated in Fig. 6, wherein the button is shown as provided with an internally-threaded socket for the reception of the 70 externally-threaded upper end of the shank

4. It may be stated, further, that I do not contemplate the use of rubber buttons exclusively, inasmuch as it may be expedient, and possibly preferable, to employ kid, velvet, 75 plush, or other similar materials capable of that degree of contraction and expansion which is necessary to the effective operation of the clasp. The manner of attachment of the elastic or other strips constituting the 80 garment-supporter may be effected in a variety of ways; but the end of the member 1 beyond the hinge 3 is preferably slotted, as shown, and the elastic is passed therethrough and secured in any well-known manner—as, 85 for instance, by sewing.

From the foregoing it will appear that I have produced a simple, inexpensive, and effective clasp of the character described embodying a construction best calculated to effect the accomplishment of the several objects stated; but while this embodiment of the invention is thought at this time to be preferable I desire to reserve the right to effect such changes, modifications, and variations as may 95 be comprehended within the scope of the protection prayed.

What I claim is—

1. The combination of a base-plate having a stud provided with an elastic head larger 100 than the neck of the stud, and another plate having an opening for receiving the button with the fabric on it to be clasped, said opening having outwardly-expanding form, and adapted to contract the button in entering 105 the opening, and permit the expansion of the surface of the button in the opening after entering it, said parts being hinged together.

2. A clasp comprising a button member having a yielding button over which the fabric is clamped, and a co-operating eye member provided with a transverse eye having a rounded inner edge, a flared outer end and a constricted portion intermediate of the flared end and rounded edge, whereby the fabric 115 may be passed into the eye without injury and will be expanded with the button when the latter is forced beyond the constricted portion of the eye, and into the flared outer end thereof.

3. The combination with a base-plate having a stud provided with an elastic head larger than the neck of the stud, and another plate designed to clamp the intermediate fabric against the base-plate and having an 120 opening for receiving the button with the fabric on it to be clamped, said opening having an outwardly-expanding form and adapted to contract the button on entering the opening, and to permit the expansion of the 125 surface of the button in the opening after entering it.

4. A clasp comprising a button member having a contractile button supported by a

shank or neck, and an eye member having an eye comprising a constricted portion of true cylindrical form and longitudinally coextensive with the shank or neck, and said eye being flared from said constricted portion, whereby the button in one position thereof will be located within the flared portion of the eye immediately beyond the constricted portion thereof.

10 5. A clasp of the character described having a yielding button upon which the fabric is clamped, and a coöperating eye member, the eye of which is formed by a laterally-

disposed annular flange having an interior bevel at its outer edge to define an expanded portion of the eye within which the yielding button is designed to expand to its normal size for the purpose of clamping the fabric against the interior surface of the flange.

In testimony that I claim the foregoing as my own I have hereto affixed my signature in the presence of two witnesses.

ELLA N. GAILLARD.
